C. F. PINE

POLE

Filed July 8, 1927

INVENTOR
C. F. Pine,
BY *Murphy & Co.*
ATTORNEY

UNITED STATES PATENT OFFICE.

CHARLES F. PINE, OF OKLAHOMA CITY, OKLAHOMA.

POLE.

Application filed July 8, 1927. Serial No. 204,359.

This invention relates to poles and fence posts.

An object of the invention is the provision of an upright in the form of a pole or post which is stamped from a single piece of sheet metal in such a manner that a sufficiently rigid and durable structure will be had which will resist the wear and strain of a fence or telegraph lines.

Another object of the invention is the provision of a post or telegraph pole which will readily ground electric currents and afford a protection to linemen when making repairs or when employed as a fence post will act as a ground protection to cattle during thunderstorms.

A further object of the invention is the provision of a telegraph pole of such knock-down construction that the parts may be shipped in compact bundles and readily assembled with a minimum of effort where the poles are to be erected.

A still further object of the invention is the provision of a metal pole or post which may be employed as a base in the reclamation of wooden telegraph poles which have rotted below the ground line.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claim.

In the drawings:—

Figure 1 is a view in perspective of a metal fence post constructed according to the principles of my invention.

Figure 2 is a view in perspective of a telegraph pole evolved from a modification of the fence post shown in Fig. 1.

Figure 3 is a horizontal section taken along the line 3—3 of Fig. 1.

Figure 4 is a view in perspective of a reclaimed telegraph pole in accordance with the principles of my invention, and

Figure 5 is a horizontal section of the modified form shown in Fig. 4.

Referring more particularly to the drawings 10 designates a wire fence supported by improved post 11 which is formed of metal and stamped from a single sheet.

The post has a base 12 horizontally disposed from which rises a standard 13 at a right angle to said base. The standard tapers from the lower or base portion 14 to 60 the extreme upper end 15.

Flanges 16 are bent inwardly from the side edges of the standard to reinforce the post and are inclined towards each other from the inturned flanges 17. The last 65 mentioned flanges are integrally formed between and with the lower ends of the lateral flanges 16 and the side edges of the base member or footing 12 and are pressed into close contact with said base 70 member.

Along a medial line of the standard a rib 18 is pressed or stamped to facilitate the application of a wire netting or fence to said posts. The rib is perforated to receive bolts or staples 19 which secure the strands of the netting to the posts.

In the modification illustrated in Fig. 2, a telegraph pole is evolved from the simplified form of post shown in Fig. 1. This 80 pole consists of a pair of posts 20 and 21 bolted together at 22 with the standards 23 in flat engagement. The standards rise from oppositely disposed base members 24 and 25 arranged in the same horizontal 85 plane.

The post 20 is reinforced by lateral flanges 26 which are tapered throughout their length and are progressively inclined inwardly from the lower ends thereof to the 90 extreme upper ends, the inclination conforming to the tapering of the standard 23 of post 20.

The lower ends of the lateral flanges are continued at 27 in flat contact with the base 95 member 24 and merge as an integral construction into said base member. The flanges 26 and standard 23 cooperate to form a channel member for a purpose which will be presently explained.

The post 21 is identical in construction with post 20 and has the lateral flanges 30 cooperating with the standard to provide a channel member with the lateral flanges tapering from the base member 25 to the 105 upper ends and inclined towards each other progressively from the lower to the upper extreme ends. The flanges are continued in contact at 31 with the base member and merge into the base member as an integral 110 formation with the base.

The posts are increased in height to pro-

- vide a pole formation by a pair of bars 32 and 33 which are spaced from each other by blades 34 and secured together by bolts 35 passing through the base and blocks. 5 The lower end of the base or bar 32 is received within the upper end of the channel of the post 20 while the lower end of beam 33 is received within the upper end of the channel of post 21. Bolts 36 passing 10 through alined passages in the beams and standards 23 of the posts secure the beams to the posts.
- Transverse bars 37 and 38 are respectively set in notches 39 and 40 in the beams and 15 are secured in any approved manner to said beams. To these bars are adapted to be secured the insulating supports for the telegraph wires.
- It is possible by my improved post construction to reclaim telegraph poles which have become useless by the rotting away of 20 that portion of the pole which is located below the ground line. A pair of the similarly constructed metal posts 20^a and 21^a 25 are placed in contact with the base members 41 and 42 in horizontal alinement. A slot 43 is formed longitudinally through the lower end of the pole and the contacting standards of the posts are fitted into the slot. 30 Bolts 44 are passed through alined passages in the pole and standards and are secured in place for binding the pole to the posts. The projecting ends of the posts form a new 35 footing for the pole and replace the part of said pole which has been discarded. The flanges 46 and 47 of said posts embrace opposite sides of the pole at each side of the slot 43 and aid in retaining the pole and posts in a fixed relation to each other.
- 40 The posts are stamped from a single sheet of metal and may be fitted into each other to provide a compact bundle for shipping.

In the construction of the telegraph pole shown in Fig. 2, the parts may be associated readily and conveniently at the place where the poles are to be erected thus decreasing the cost in shipping. The beams 32 and 33 may be bolted together at the factory so that it will only be necessary to slip the spaced lower ends of said beams over the assembled posts before erection. 45

In Fig. 1, tapering ribs 60 are formed by stamping the standards 13 and provide additional reinforcing means for the posts.

By the employment of the poles and posts constructed according to the principle of my invention it will be noted that a great saving in labor and material will be had, particularly in view of my method of setting the poles on the ground or on a concrete 55 base of limited depth. The footings of the poles or posts vary advantageously to provide for a rapid positioning of the poles or posts and at a minimum cost. 60

I claim:—

A device of the character described comprising a standard tapering from one end to the opposite end, tapering flanges projecting laterally from the edge of the standards and formed integrally therewith, a base member formed integrally with the tapering standard and located at substantially right angles to the said standard, said flanges having portions disposed in flat contact with the base member and merging into and integrally connected with portions of the base member, said flanges, standard and base member being formed of a single sheet of metal, the portions of the flanges where connected to the base providing a reinforcing 75 means between the base member, the standard and the flanges. 80

CHARLES F. PINE.
